CLAIM

The ornamental design for a conduit riser cover, as shown and described.

DESCRIPTION

FIG. 1 is an isometric view of a conduit riser cover;

FIG. 2 is front view thereof;

FIG. 3 is a rear view thereof;

FIG. 4 is a left-hand side view thereof;

FIG. 5 is a right-hand side view thereof;

FIG. 6 is a top view thereof;

FIG. 7 is a bottom view thereof; and,

FIG. 8 is another isometric view of the conduit riser cover in an open position for illustration.

The broken lines shown in the drawings illustrate the environment of the article and form no part of the claimed design.
